Atty.

UNITED STATES PATENT OFFICE.

MAX BUCH, OF DETROIT, MICHIGAN.

TOP FOR VEHICLES AND THE LIKE.

1,275,214.

Specification of Letters Patent. Patented Aug. 13, 1918.

Application filed February 21, 1916. Serial No. 79,697

To all whom it may concern:

Be it known that I, MAX BUCH, a subject of the Emperor of Germany, residing at Detroit, Michigan, have invented certain new and useful Improvements in Tops for Vehicles and the like, of which the following is a specification.

My present invention relates to improvements in tops, hoods or covers designed for use on vehicles of any kind, motor-boats, etc., and has for its object to provide an extremely simple, economical and efficient construction, which may be folded and unfolded by a single operator without disturbing the occupants of the vehicle and which will dispense with the necessity for the use of what are known as strainers between the several bows, which are designed to relieve the covering of the strain imparted by the weight of the frame when the top is in its unfolded or extended position.

With these and other objects in view, the invention includes the novel features of construction and arrangement and combination of parts hereinafter described and particularly defined by the appended claims. Two embodiments of my invention are illustrated in the accompanying drawings, in which—

Figure 1 is a side elevation of a top in its extended position.

Fig. 2 is a view showing the said top in a partly folded position.

Figs. 3 and 4 are views of modifications.

Referring by reference characters to these drawings, the numeral 1 designates the main bow, 2 the rear bow and 3 the outrigger bow. This latter has its rear ends connected to the main bow by upper and lower sets of links 4 and 5 respectively. The lower links 6 are pivotally connected to the side arms or standards of the main bow 1 by pivots, indicated at 5^a, and to the rear ends of the arms of the bow 3 by stop hinges, as indicated at 5^b. The upper links 4 are connected at their rear ends to the side arms or standards of the main bow 1 by pivots indicated at 4^a and at their forward ends to the arms of the bow 3 by pivots 4^b, which are located some-

what in advance of the stop hinges 5^b. The links 5 are provided with extensions which, in the form shown in Fig. 1, are in the rear of the pivots 5^a, indicated at 5^c, and these extensions are connected by a flexible device 6, such, for example, as a wire rope, with the rear bow 2. This flexible element, connecting said rear bow to the extension with the front bow 1, avoids the necessity of the use of strainers between said bows 1 and 2, while at the same time in the folding of the top said flexible element 6, acting on the extension of the link, serves to cause the portion of the top frame in advance of the bow 1 to fold practically in a horizontal line, causing the stop hinge 5^b to break downwardly and the front end of the bow to move rearwardly without dropping.

If the space between the main bow 1 and the outrigger bow 3 be such as to require an intermediate support, I may provide an auxiliary bow 7 having its arms pivoted at 7^a to their lower extremities to the links 5, as indicated at 7^b, and having their intermediate portions slidably connected as by pin and slot connections, indicated at 7^c, with the links 4.

In the form shown in Fig. 3, I connect the cables 6 to extensions 5^x, which are located on the upper links, which links are designated at 4^x in this view.

If desired a rear auxiliary bow may be provided between the bow standards 1 and 2, such an auxiliary bow being indicated at 8 and having its extremities pivoted to the standards 1. In such case the auxiliary bow 8 would be connected by a flexible element 6^a to the arm or extension 5^c. In this event the cable 6 might, if desired, be dispensed with.

Having thus described my invention, what I claim is:

1. In a vehicle top a main bow standard, a main rear bow arm, an outrigger bow, a pair of links pivotally connected to said standard one above the other and to said outrigger bow, one in advance of the other, one of said links having a part extending in

rear of its pivot, and a flexible link directly connecting said extended part with the main rear bow arm.

2. In a vehicle top a main bow standard, a main rear bow arm, a rear supplemental bow arm, an outrigger bow arm, a pair of links connecting said outrigger bow arm to the standard, one of said links having an extension, means connecting said extension

to the rear supplemental bow arm, and a flexible connection from said extension to the main rear bow arm.

In testimony whereof, I affix my signature in presence of two witnesses.

MAX BUCH.

Witnesses:

B. E. SILLINGTON,
E. M. WALKER.

Correction in Letters Patent No. 1,275,214.

It is hereby certified that Letters Patent No. 1,275,214, granted August 13, 1918, upon the application of Max Buch, of Detroit, Michigan, for an improvement in "Tops for Vehicles and the Like," were erroneously issued to the inventor, said Buch, as sole owner of said invention, whereas said Letters Patent should have been issued to *Henry E. Edwards, of Jackson, Michigan*, as assignee of the *entire right*, as shown by the records of assignments in this office; and that the said Letters Patent should be read with this correction therein that the same may conform to the record of the case in the Patent Office.

Signed and sealed this 17th day of September, A. D., 1918

[SEAL.]

R. W. H. CLAY,

Acting Commissioner of Patents.

Cl. 21--62.
